UNITED STATES PATENT OFFICE.

CHARLES A. CHANNELL, OF CHICAGO, ILLINOIS, ASSIGNOR TO CHANNELL CHEMICAL COMPANY, A CORPORATION OF ILLINOIS.

FLOOR MOP.

Original application filed August 9, 1917, Serial No. 185,235. Divided and this application filed November 21, 1921. Serial No. 516,553.

To all whom it may concern:

Be it known that I, CHARLES A. CHANNELL, a citizen of the United States, and resident of Chicago, county of Cook, State of Illinois, whose post-office address is % Channel Chemical Company, 4501 So. Western Boulevard, Chicago, Illinois, have invented certain new and useful Improvements in Floor Mops, of which the following 10 is a specification.

My invention relates to floor mops, the subject matter of this invention having been originally set forth in my previous application, Serial No. 185,235, filed August 9th, 15 1917, of which this application is a division.

One of the objects of my invention is to reduce the number of parts entering into the make-up of an article of this character and the production of such an article with 20 a minimum amount of labor and material; another object of my invention is such an arrangement as will permit of all the parts being stamped from sheet metal ready for assembly thus reducing the amount of hand 25 labor. In this specification and the drawings I show my novel devices in their preferred form, but it should be understood that I do not limit my invention to the form shown. Further advantages of my invention 30 will be more clearly understood by references to the following description taken in connection with the accompanying drawings in which—

Fig. 1 is a plan view of the mop. 35 Fig. 2 is a section on line 2—2 of Fig. 1. Fig. 3 is a section on line 3—3 of Fig. 2. Fig. 4 is a detail showing a step in the assembly of the parts.

The complete article comprises a mop 1 having a binding 2. This binding 2 is placed around and suitably held against the metal head 3. The head 3 comprises a top plate 4 having an upstanding flange 5 extending therearound and a lower plate 6 40 having projections 7 extending around the outer surface thereof. These two plates are held together by metal 8 which is punched out of the top plate 4 and which is extended through an opening in the plate 6 and which 45 is thereafter riveted in place. It will therefore be seen that the metal punched out to form the openings 9 is used as a rivet to hold the top and bottom plates together. 50

The device is provided with a handle

socket 10 which is made from a single piece 55 of metal. This handle socket has a portion 11 which is bent around a pin 12 located between up-set portions 13 on the top plate and an off-set portion 14 of the lower plate. The handle socket extends through an opening in the upper plate. The metal of the plate 4 is struck up just in front of the handle socket at 18 so as to form a positive stop for the handle socket. This stop is formed by a mere bending out of the metal 60 and not by rupturing it at any point, thus forming a very strong and durable stop.

The band 2 of the mop 1 is sewed together at 15.

The mode of assembly is as follows:—The 70 plate 4 is formed as shown in Fig. 2, except the metal 8 stands straight down as shown in dotted lines. The plate 6 is formed as shown in Fig. 4, that is, with the projections 7 extending substantially vertically. 75 The pin 12 is placed in its proper place with the handle socket 10 therearound, and the two plates 4 and 6 are placed together with the metal 8 extending through the openings in the bottom plate and they are then riveted 80 together. The mop 1 is then placed in position around the flange 5 and the projections 7 are moved outwardly as shown in Figs. 2 and 3 so as to hold the mop securely 85 in place. The band 2 of the mop 1 is so arranged that it extends a short distance above the top of the flange 5 of the top plate 4. The handle socket 10 is so arranged that it is adjustable around the pin 12 so that the device may be used in the well known 90 manner.

The portion of the handle socket in which the handle is inserted is locked by a dovetail projection 16 and is also provided with screw-threads 17 for the reception of a 95 screw-threaded handle.

From the foregoing, it will be apparent that the device is very simple, the same comprising only four metal parts and a mop. These parts are the top plate 4, the bottom 100 plate 6, the handle socket 10, and the pin 12 and the mop 1. By the arrangement above described, a device is secured which is rugged and will stand all the uses to which such an article is to be subjected. At the 105 same time, it is light, inexpensive and easily manufactured.

Having described my invention, what I

claim as new and desire to secure by Letters Patent is:—

1. In a mop head comprising an upper plate having means against which the mop fabric can normally be held, a lower plate provided with a downwardly and outwardly projecting flange to hold the mop against the upper plate, a movable handle socket mounted on said head by means of a pivot pin held between said plates and around which a portion of the socket is bent.

2. In a mop head comprising an upper plate having a flange against which the mop fabric can normally be held and a lower plate provided with a downwardly and out-

wardly projecting flange, said flange being adapted to engage and hold the mop against the flange of the upper plate, a pin secured between said plates, a movable handle socket mounted on said head, said socket comprising a single piece of metal, a portion of which is bent around said pin, said socket extending through said upper plate and an upturned integral portion of said upper plate acting as a stop to limit the movement of said handle socket around said pivot in one direction.

In testimony whereof, I have signed my name to this specification.

CHARLES A. CHANNELL.
